CLAIM

The ornamental design for a vacuum cleaner-blower,
substantially as shown and described.

DESCRIPTION

FIG. 1 is a perspective view of a vacuum cleaner-blower showing our new design;

FIG. 2 is a side elevational view thereof shown on a
slightly enlarged scale;

FIG. 3 is a top plan view thereof; and

FIG. 4 is a bottom plan view thereof.

*Fig. 1.**Fig. 2.**Fig. 3.**Fig. 4.*
